UNITED STATES PATENT OFFICE.

GIULIO MARCHETTI, OF HALIFAX, ENGLAND.

DESIGN FOR A CARPET.

SPECIFICATION forming part of Design No. 23,363, dated June 12, 1894.

Application filed April 17, 1894. Serial No. 507,928. Term of patent 3½ years.

To all whom it may concern:

Be it known that I, GIULIO MARCHETTI, a subject of the Queen of Great Britain, and a resident of Halifax, in the Kingdom of England, have invented a certain new and original Design for Carpets and Borders, of which the following is a specification.

The accompanying drawing is a face view of a portion of a carpet embodying my design.

My design is especially adapted to be worked in stair carpets. It comprises a series of essentially diamond shaped figures defined by wavy stem work bearing small flower forms. Within these figures worked in the body of the carpet are smaller diamond shaped figures, each defined by a serrated line, and having shield shaped or pendant-like ornaments at their lower ends. In the center of the figures are sprays of flower forms surrounded by one or more circlets of curving stem work or flower forms. In the

figures running along the edges of the carpet there are no concentric diamond shaped figures defined by serrated lines. There is however in each figure a central spray of flower forms surrounded by a circlet of flower forms with a pendant like ornament at the bottom and the space between the circlet and outer stem work is characterized by line work. The outer sides of contiguous figures are joined by bands of flower forms.

What I claim as my design, and desire to secure by Letters Patent, is—

The design for a carpet, substantially as shown and described.

In testimony whereof I have signed my name to this specification in the presence of two subscribing witnesses.

GIULIO MARCHETTI.
